UNITED STATES PATENT OFFICE.

EDWARD H. CROSBY, OF BOSTON, MASSACHUSETTS, ASSIGNOR TO THE CROSBY ELECTRIC COMPANY, OF NEW YORK, N. Y.

GALVANIC BATTERY.

SPECIFICATION forming part of Letters Patent No. 437,393, dated September 30, 1890.

Application filed February 8, 1890. Serial No. 339,628. (No model.)

To all whom it may concern:

Be it known that I, EDWARD H. CROSBY, of Boston, in the county of Suffolk, State of Massachusetts, have invented certain new and useful Improvements in Galvanic Batteries, of which the following is a description sufficiently full, clear, and exact to enable any person skilled in the art or science to which said invention appertains to make and use the same, reference being had to the accompanying drawing, forming part of this specification, in which—

The figure of the drawing is a vertical transverse section of my improved battery.

15 My invention relates especially to that class of open-circuit batteries known as "dry batteries;" and it consists in certain novel features hereinafter fully set forth and claimed, the object being to produce a simpler, cheaper, 20 and more effective device of this character than is now in ordinary use.

The nature and operation of the improvement will be readily understood by all conversant with such matters from the following 25 explanation.

In the drawing, A represents the containing-jar, which is constructed of pasteboard, wood fiber, paper-stock, or similar cheap material, and is provided with a tight-fitting 30 cover b. The material of the jar is covered on its outer face with a coating of shellac d, and on its inner face is coated with a preparation f, compounded of paraffine and ozocerite or other suitable acid-proof substance. A 35 zinc cylinder D is disposed within the containing-jar, and is preferably formed to fit tightly therein.

On the bottom of the jar A and within the cylinder D a pad C, of felt or similar absorbent material, is disposed. A stick of carbon K rests centrally upon the pad C. The space between the carbon and walls of the zinc cylinder is packed tightly with sawdust m, mixed with a dry excitant, preferably sal-ammoniac. The pad C is saturated with a 45 mild solution of sulphuric acid or other excitant. Connectors p v are respectively se-

cured to the zinc and carbon and project through suitable openings in the cover b.

Instead of the zinc cylinder described a strip 50 or pencil of zinc may be employed. As thus constructed the battery can be very cheaply manufactured and readily transported without injury, the containing-jar forming a packing-case therefor.

I do not confine myself to employing sawdust as a packing between the zinc and carbon, as any cheap material which can readily be mixed with a dry excitant will effect similar results.

The pad C, disposed in the bottom of the jar and cover by the sawdust or similar material, as described, retains its moisture for a long time, and it is found that this arrangement of the parts greatly increases the electro-motive force of the battery. The life of the battery is much longer than those of ordinary construction, and by slightly moistening the pad it can readily be renewed.

Having thus explained my invention, what I claim is—

1. A containing-jar for electric batteries, constructed of paper-stock or similar material prepared with an outer coating of shellac and an inner acid-proof coating compounded 75 of paraffine and ozocerite, substantially as described.

2. In an electric battery, an acid-proof containing-jar, an absorbent pad disposed therein, a zinc plate, and a carbon plate resting on 80 said pad and surrounded by a packing containing a dry excitant, substantially as described.

3. In an electric battery, the combination of an acid-proof containing-jar, a zinc plate, 85 an absorbent pad saturated with an excitant, and a carbon plate in contact with said pad and surrounded by a packing containing a dry excitant, substantially as described.

4. In an electric battery, a packing separating the positive and negative plates and comprising sawdust or wood fiber mixed with an excitant in a dry or crystalline form, substantially as described.

5. In an electric battery, the combination of a paper containing jar coated with an acid-proof composition, a zinc plate, a pad of absorbent material disposed within said jar and containing a liquid excitant, a carbon plate on said pad, and a packing comprising sawdust and a dry or crystalline excitant sur-
- rounding said carbon, substantially as set forth.

EDWARD H. CROSBY.
